UNITED STATES PATENT OFFICE

FREDERICK WILLIAM ATACK, OF KINGSTON, ONTARIO, CANADA, ASSIGNOR TO INDUSTRIAL PROCESSES DEVELOPMENT, LIMITED, OF TORONTO, ONTARIO, CANADA, A CORPORATION OF CANADA

EMULSION

No Drawing. Application filed March 6, 1928, Serial No. 259,593, and in Great Britain April 19, 1927.

This invention relates to emulsions of grease solvents and to a process of manufacture thereof. The object is to provide emulsions which are fluent, i. e. immediately miscible with water, and yet are stable. 5 Further objects are to provide novel emulsions and detergent compositions containing grease solvents, notably chlorinated hydrocarbons.

It has been proposed to prepare emulsions of certain grease solvents by incorporating them with bentonite and soap, when a gelatinous pasty or viscous mass is obtained which, when prepared properly, is stable but not fluent since it does not mix immediately with water. I have now discovered a method whereby it is possible to obtain fluent emulsions of such solvents which are still stable. To this end the invention comprises the methods and compositions as hereinafter described and claimed.

Example 1

By way of example, a suitable emulsion 25 contains (parts by weight):—

67% trichlorethylene.
4½% Turkey red oil.
2% bentonite.
26% water.
30 0.45% ammonia (.880).

The ammonia is added in the form of a dilute solution in part of the water while the bentonite is previously suspended as an 8% 35 suspension in the remainder of the water.

Other emulsifying agents may be used instead of Turkey red oil, but it is desirable to avoid substantial quantities of gelatinizing ingredients such as common soap.

40 If substantial quantities of soap are used, a gelatinous composition is obtained which does not mix immediately with water, whereas the product of the present invention is liquid and fluent and it immediately mixes 45 with water.

Example 2

24 lbs. of bentonite are suspended in 300 lbs. of water, 30 lbs. of Turkey red oil are 50 added, and 120 lbs. of trichlorethylene added

with rapid stirring, 45 lbs. of fatty acids are added with stirring, followed by sufficient alkali to give a slightly alkaline product (not over 4 lbs. of 50% caustic soda solution). The object of added alkali is to guard against 55 liberation of mineral acid from the chlorinated solvent. It is advantageous to begin with the mixture of water and bentonite as described.

The product is an aqueous emulsion of remarkable stability and even on great dilution gives stable emulsions.

In this example the 120 parts of trichlorethylene may be replaced by a mixture of 90 parts of trichlorethylene and 30 parts of 65 tetrahydronaphthalene.

The term "bentonite" is used to include colloidal siliceous materials having the characteristic bentonitic property, namely that by stirring with water they can be transported 70 into a stable dispersion. The term chlorinated hydrocarbon includes hydrocarbons containing chlorine whether prepared by an actual chlorination process or not; trichlorethylene is only given by way of example. 75 Other grease solvents may be used, e. g. hydrogenated hydrocarbons or hydrogenated phenols.

Among other uses for the novel emulsions, they may be employed as detergents in laundering, carpet cleaning, etc.; for the scouring and finishing of wool; for kier-boiling and finishing of cotton goods; for scouring, dyeing and finishing of artificial silk in one bath process; for scouring, dyeing and finishing of mercerized cotton; for degumming of silk; as assistant in wetting out and leveling dyeing, especially of artificial silk; for deinking of printed paper stock; and for general detergent purposes, such as in dishwashing machines, household cleaning, paint cleaning etc.

The emulsions may also be mixed with solid materials and a useful detergent consists of a mixture of one part of the product 95 of Example 1 or 2 with six parts of soda ash and three parts of sodium bicarbonate.

I declare that what I claim is:—

1. A liquid aqueous emulsion immediately 100 miscible with water containing a liquid chlo-

rinated hydrocarbon, Turkey red oil and bentonite, and exhibiting a weak alkaline reaction.

5 2. A liquid emulsion containing a liquid chlorinated hydrocarbon in greater quantity than any other ingredient, water, Turkey red oil as primary emulsifier, bentonite, and a small proportion only of soap.

10 3. A stable liquid emulsion instantly miscible with water, containing water, a liquid grease solvent substantially immiscible with water, a primary emulsifying agent which is a sulphonated product derived from a glyceride and capable of forming a transient emulsion instantly miscible with water, and bentonite as a stabilizer of said emulsion.

15 In witness whereof, I have hereunto signed my name this first day of March 1928.

FREDERICK WILLIAM ATACK.
